UNITED STATES PATENT OFFICE.

ADOLPHUS PETERSON, OF BROOKLYN, ASSIGNOR OF ONE-HALF OF HIS
RIGHT TO SILAS C. CROFT, OF NEW YORK, N. Y.

IMPROVEMENT IN CARPET-EXHIBITORS.

Specification forming part of Letters Patent No. 222,730, dated December 16, 1879; application filed October 23, 1879.

To all whom it may concern:

Be it known that I, ADOLPHUS PETERSON, of Brooklyn, in the county of Kings and State of New York, have invented certain new and useful Improvements in an Adjustable Carpet-Exhibitor, of which the following is a full, clear, and exact description, which will enable others skilled in the art to make and use the same, reference being had to the accompanying drawings, forming part of this specification, in which—

Figure 1 represents a side elevation. Fig. 2 is a plan of the same. Fig. 3 is a sectional end elevation.

Similar letters of reference indicate corresponding parts.

Heretofore multiplying-mirrors have been used for exhibiting carpets and other samples of goods; but all such devices have been cumbersome and inconvenient to manipulate, and in order to operate them the mirrors had either to be clamped together by spring-clasps or hinged vertically at the corners, and these held secure by hooks, making it necessary for the exhibitor in all cases to lift or slide at least two of the sections of mirrors upon the face of the carpet each time a fresh pattern is required to be shown.

The object of my invention is to construct an exhibitor which will remain stationary on a suitable table or platform, and at no time move any of its parts across or over the face of the carpet being exhibited. The various samples or patterns of different widths, having their ends connected, are wound on rollers situated below the table or platform, which serve to draw the pattern or patterns smoothly and evenly across the plane of the table with the edge under the fixed mirror; and when any particular pattern which seems to please the purchaser passes over the table the hinged mirror is adjusted to position by sliding the extension-leaf up to the pattern, and the said mirror raised vertically, so that its base may rest upon the edge of the sample, for the purpose of still further multiplying the pattern. The great advantage gained in having the near mirror hinged to and supported upon the extension-leaf is so that it may be laid flat while the patterns are being run across the

table, with a full unobstructed light on the same, the said extension-leaf having one or more dovetailed tongues, which extend through corresponding mortises in the main frame, for the purpose of keeping the movement of the sliding mirror parallel to the fixed mirror, as well as serving to support the carpet or other sample from sagging in the gap when exhibiting a wide piece of goods.

In the case here presented, A A represent a rigid rectangular mirror, rigidly attached to the table B, the said table being provided with ways C C or their equivalent, for the purpose of receiving and holding an extension or sliding leaf, D, on whose outer side the mirror E is hinged, as shown at F, the said mirror being held in vertical position, when desired, by means of a sliding bolt, G, as shown in Figs. 1 and 2.

Between each pair of the table-legs, or between suitable brackets attached thereto, the rollers H H' have their bearings. Upon these rollers the samples of carpet or other goods are wound, so that the carpet being wound off one may be wound on the other, and thereby kept tight and smooth on the plane of the table. I I are pawls, which engage the teeth of the ratchet-wheels J J, and serve to hold the rolls from slipping back. K K are friction-rollers, extending the full width of the table.

Having thus described my invention, what I claim as new, and desire to secure by Letters Patent, is—

1. The combination, in a sample-exhibitor, of the rigid rectangular mirror A A, table B, and ways C C with the sliding extension-leaf D and horizontally-hinged mirror E, for the use and purpose substantially as shown and described.

2. The combination, in a sample exhibitor, of the adjustable sliding mirror E and fixed rectangular mirror A A with the rollers H H and friction-rollers K K, all arranged and operating together in the manner and for the use and purpose specified.

ADOLPHUS PETERSON.
